UNITED STATES PATENT OFFICE.

CLARK E. SULLIVAN, OF GRAND RAPIDS, MICHIGAN.

PIPE-WRENCH.

1,177,660.

Specification of Letters Patent.

Patented Apr. 4, 1916.

Application filed March 23, 1915. Serial No. 16,377.

To all whom it may concern:

Be it known that I, CLARK E. SULLIVAN, a citizen of the United States, residing at Grand Rapids, in the county of Kent and 5 State of Michigan, have invented certain new and useful Improvements in Pipe-Wrenches; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this specification. 15

This invention relates to new and useful improvements in pipe wrenches and the object in view is to produce a simple and efficient device of this nature so constructed 20 that the downward pull upon the handle will cause the jaws to move in opposite directions, thus affording a secure grip upon an object.

The invention comprises various details of 25 construction, combinations and arrangements of parts which will be hereinafter fully described, shown in the accompanying drawings and then specifically defined in the appended claim.

30 I illustrate my invention in the accompanying drawings, in which:

Figure 1 is a side elevation of a wrench made in accordance with my invention. Fig. 2 is a sectional view longitudinally through 35 rack and pinion mechanism, and Fig. 3 is a cross sectional view on line 3-3 of Fig. 1.

Reference now being had to the details of the drawings by letter, A designates a jaw 40 having a shank portion B and serrations C upon the inner edge thereof, and D designates a jaw having a hollow offset portion adapted to receive the shank B of the jaw A.

Projecting from one edge of the jaw D is a 45 shank portion E having teeth F upon one edge thereof. A handle, designated by letter H, has an offset portion H' and has an integral pinion wheel K', the teeth K of which are adapted to engage the teeth upon 50 said shank at positions diametrically oppo-

site and affording means whereby, as the handle is turned in one direction or the other, the two jaws will be caused to move in opposite directions. A rivet, designated by letter L, is passed through one end of the 55 handle and centrally through the said integral gear wheel K' and retains a washer O which, coöoperating with the adjacent face of the handle, serves to guide the cog teeth upon the shank portions of the jaws as the handle 60 is turned.

In operation, it will be noted that, by the provision of a wrench made in accordance with my invention, a double action is afforded wherby, as the handle is drawn down, the 65 shank portion B of the jaw A is caused to move to the right, while the jaw D will be moved in the opposite direction, thereby forming a secure gripping action upon an object which is held to the nut securely by 70 increased pressure and on a reverse swinging movement of the lever the jaws will be thrown away from each other.

What I claim to be new is:—

A pipe wrench comprising a jaw having 75 a shank portion with serrations upon its inner marginal edge, a second jaw having a hollow offset portion adapted to receive the shank of the other jaw and provided with a shank portion having serrations upon one 80 edge thereof, the face of the second referred to jaw being recessed, a handle having a circular-outlined end with a laterally extending boss, which has circumferential teeth thereon adapted to engage the teeth upon 85 the adjacent edges of the shank portions of said jaws, the circumference of said circular-outlined part of the handle movable within the recess in the face of said second referred to jaw, a pin passing through said boss, and 90 a disk held by the screw against the corresponding faces of the shank portions of the jaws.

In testimony whereof I hereunto affix my signature in presence of two witnesses.

CLARK E. SULLIVAN.
